UNITED STATES PATENT OFFICE.

WILBUR B. BURKE, OF CLEVELAND, OHIO, ASSIGNOR TO A. SCHRADER'S SON, INCORPORATED, OF BROOKLYN, NEW YORK, A CORPORATION OF NEW YORK.

DUST-CAP FOR VALVES OR THE LIKE.

1,253,573.

Specification of Letters Patent. Patented Jan. 15, 1918.

Application filed March 26, 1915. Serial No. 17,178.

To all whom it may concern:

Be it known that I, WILBUR B. BURKE, a citizen of the United States, residing at Cleveland, in the county of Cuyahoga and 5 State of Ohio, have invented new and useful Improvements in Dust-Caps for Valves or the like, of which the following is a specification.

This invention relates to dust caps for 10 valves or the like and aims to provide certain improvements therein.

The features of the invention will be hereinafter more fully described and pointed out in the claims.

15 Referring to the drawings which illustrate several forms of the invention, the Figure 1 is a longitudinal section of one form of the invention. Fig. 2 is a longitudinal section of another form of the invention. 20 Fig. 3 is a side elevation of Fig. 1. Fig. 4 is a bottom view of Fig. 1, and Fig. 5 is a top view thereof.

25 Referring to Fig. 1 of the drawings let A. indicate the cap portion or shell which is preferably drawn of suitable metal and preferably has an enlarged foot portion —B. Between the cap portion and the foot portion is formed a shoulder —C. Resting upon the shoulder C. is a nut portion, D., which is constructed in the form of a bushing. This is provided with a threaded bore, E., designed to screw over the valve shell. In the construction of Fig. 1 the bushing, D., is retained in place by compressing the 30 metal, F., of the cap portion into contact with the bushing. This may be done by squeezing the metal against the bushing or the metal may be turned over as shown at G.

35 In Fig. 2, the cap portion, A', is substantially the same in shape and construction as the cap portion A of Fig. 1. The bushing, D', however is formed of a plurality of parts. These parts comprise a threaded portion, H., and two flat portions, I. and J., respectively. The threaded portion, H., is formed with a flange, H', which fits between the flat portions I. and J., and is also formed with a flange, H² extending at right angles with the flange H', and parallel with the 40 longitudinal axis of the cap.

45 The cross section of the cap portion, A., may be of any suitable shape, as for instance round or hexagonal, and the foot portion, B., is also preferably hexagonal, or other 50 non-circular contour. In this case the bush-

ings will preferably correspond to the shape of the foot portion, so that when they are introduced into the foot portion they will form a non-circular connection therewith. This connection is an efficient and durable 60 one and prevents any possibility of looseness between the parts when they are due to torsional strains in screwing and unscrewing the cap. The compression of the foot portion about the bushing securely holds the 65 bushing in place so that the parts cannot separate in a direction which is longitudinal of the cap.

A feature of importance in connection with the invention is the formation of a cap 70 portion of steel or other cheap metal in combination with a bushing of brass or other non-corrosive metal. As dust caps are exposed to moisture the threaded portion of the cap must be formed of a metal which 75 will not rust. For this reason it has been the custom heretofore to form the entire cap of brass, which has resulted in an expensive cap. By the present invention the principal advantages of a brass cap are secured without the attendant expense. The cost of the 80 cap of Fig. 1 may be further reduced by the construction of Fig. 2, wherein the bushing, H., may be made of brass and the plates or blanks, I. and J., of iron or of a cheap metal. 85 The weight of the bushing, H., is hence very materially reduced as compared with the bushing D., of Fig. 1, while an effective and durable construction is at the same time obtained.

90 In either figure a space is preferably left at the bottom of the cap as shown wherein may be introduced a leather or other washer adapted to bear against the wheel rim or rim nut, if the latter is used.

95 While I have shown and described several forms of the invention, it will be understood that I do not wish to be limited thereto since various changes may be made therein without departing from the spirit of the invention.

100 What I claim as my invention is:

1. A dust cap for tire valves or the like comprising a cap portion having a polygonal foot portion with an internal shoulder above 105 it, and having means for connecting it to a threaded valve casing or the like, said means comprising a polygonal bushing of different metal from the cap portion entering and lying within and substantially inclosed by the 110

foot portion, and said foot portion being permanently connected to the bushing by overlying parts of the foot portion, the article constituting a unitary structure, whereby when the cap is rotated the bushing is forced to rotate with it.

2. A dust cap for tire valves or the like, comprising a cap portion having an enlarged polygonal foot portion and having a means for connecting it to a threaded valve casing or the like, said means comprising a separately formed polygonal bushing entering and lying within and substantially inclosed by said foot portion, and said foot portion being permanently connected to the bushing by overlying parts of the foot portion, the article constituting a unitary structure.

whereby when the cap is rotated the bushing is forced to rotate with it.

3. A cap for valves or the like comprising a cap portion having an enlarged foot portion, and bushing having a flange extending longitudinally of the cap and a flange extending transversely thereof, and a plate or blank in the recess formed by said flanges.

4. A cap for valves or the like comprising a cap portion having an enlarged foot portion, and bushing having a flange extending longitudinally of the cap and a flange extending transversely thereof, and a plate or blank in the recess formed by said flanges, and a second plate or flange on the opposite side of said bushing.

WILBUR B. BURKE.
